Patented Apr. 27, 1965

200,955

TRAILER VAN TOP

Jacob E. Patterson, P.O. Box 796, Minden, La.

Filed Oct. 6, 1964, Ser. No. 82,055

Term of patent 14 years

(Cl. D14—3)

Fig. 1

Fig. 2

Fig. 3

Fig. 4

Fig. 5

FIG. 1 is a perspective view of a trailer van top showing my new design;

FIG. 2 is a top plan view;

FIG. 3 is a side elevation;

FIG. 4 is a front end view; and

FIG. 5 is a rear end view.

The broken line disclosure in FIG. 1 is for illustrative purposes only.

I claim:

The ornamental design for a trailer van top, as shown and described.
